BUTTON ASSEMBLING MACHINE

William C. Broadwell, Palo Alto, Calif., assignor
to Assembled Products Incorporated, Milford,
Conn.

Application September 17, 1949, Serial No. 116,384

12 Claims. (Cl. 223—49)

1

This invention relates to a machine for use in assembling, with reference to each other, the essential elements of a well known type of clasp which is widely employed in such wearing apparel as hose or stocking supporters and is characterized by the fact that it includes a wire frame shaped at one end to provide a garment-receiving loop adapted to receive the shank portion of a garment-retaining button carried at one end of a flexible tab, the opposite end of which tab is secured to an anchor clip which is in turn secured to the side arms of said frame.

Heretofore the cost of assembling clasps of the above character has been excessively out of proportion with respect to other costs encountered in their manufacture, the excess cost of assembly being in a large measure due to the difficult and tiring manual operation involved in forcing the garment-retaining buttons into impinging relation to the garment-receiving loop of the wire frames as a final assembly step in conditioning the clasps for shipment.

An important object of the present invention is to provide a simple, efficient and reliable machine by which all of the assembly steps involved in the production of clasps of the above character may be carried out with pronounced accuracy and economy, such steps being those which are performed in first securing the anchor clip to the side arms of the wire frame, then in securing the flexible tab to said clip, and finally in forcing the garment-retaining button into its impinging relation to the garment-receiving loop at the end of said frame.

Other objects and advantages of the present invention will become apparent from the following description when taken in connection with the accompanying drawings, in which

Fig. 1 is a front elevation of the machine embodying the present invention,

Fig. 2 is a fragmental plan view of the feed end of the machine appearing at the right in Figure 1,

Fig. 3 is a perspective view of an anchor clip as it appears before being incorporated into the clasp,

Fig. 4 is a fragmental sectional view taken on line 4—4 of Figure 1 and showing certain details of construction common to each of a plurality of carriages constituting important elements of an endless chain-like conveyor extending longitudinally of the machine,

Fig. 5 is a fragmental sectional view taken on line 5—5 of Figure 1 and illustrating the relationship between the respective actuating means for the conveyor and the tab-folding and button-inserting unit,

2

Fig. 6 is a fragmental sectional view showing the conveyor actuating pitman rod, as seen from the rear of the machine in Figures 1 and 5, and illustrating the bell-crank connection between that rod and a reciprocatory slide unit by which the conveyor is moved step-by-step,

Fig. 7 is a sectional view taken on line 7—7 of Figure 6 and showing certain details of the slide unit as they appear during such time as the conveyor is being advanced,

Fig. 8 is a fragmental sectional view taken on line 8—8 of Figure 1 and showing the tab positioning plunger in relation to its associated crimping tool, the former of which is adapted to engage the tab and insure its being properly abutted against the anchor clip along the longitudinal line of fold thereof before the end lugs or fingers of the clip are folded over into anchoring engagement with the side arms of the wire frame,

Fig. 9 is a fragmental sectional view showing the folding arm of the tab-folding and button-inserting unit as having been moved out of its position, shown in Figure 5 and into engagement with an upstanding tab at a station following the station at which the anchor clips are folded into impinging engagement with the tabs,

Fig. 10 is a view similar to that of Figure 9 and showing the folding arm of the tab-folding and button-inserting unit as having moved the free end of the tab to such a position that the button may be forced into the garment-receiving loop of the wire frame,

Fig. 11 is a view similar to that of Figure 10, but with the tab-folding and button-inserting unit omitted and the button illustrated as having been forced into the garment-receiving loop of the wire frame by said unit,

Fig. 12 is a sectional view taken on line 12—12 of Figure 11,

Fig. 13 is a sectional view taken on line 13—13 of Figure 10,

Fig. 14 is a sectional view taken on line 14—14 of Figure 11, the arm by which the hold-down finger for the wire loop is supported being shown in full lines,

Fig. 15 is a fragmental plan view of the endless chain-like conveyor and illustrating the progress of assembly that is effected in connection with the component elements of the clasp as the upper reach of the conveyor is moved step-by-step along its path of travel from right to left,

Fig. 16 is a fragmental view showing in side elevation the conveyor-actuated driving mechanism by which its associated escapement wheel is rotated step-by-step in controlling the feeding of anchor clips to the carriages of the conveyor as

such carriages move successively into clip-receiving positions beneath said wheel, and

Fig. 17 is a fragmental view showing a pair of the conveyor carriages in relation to the conveyor-actuated driving mechanism at such time as the carriages and the driving mechanism are in their respective normal positions of rest, the carriages being shown in section on a horizontal plane substantially coincident with the upper faces of the conveyor guide rails and the vertically disposed pawl-carrying flange of the driving mechanism being shown in section on a horizontal plane passing through the same on a line slightly above the upper faces of said rails.

The machine herein illustrated as embodying the present invention is designed for use in assembling clasps, which, as will be understood from an inspection of Figures 3, 10, 11, 14 and 15, are characterized, for example, by the fact that they each comprise a wire frame 20, the side arms of which are held together in an abutting relation at one end of the frame by a suitable retaining sleeve 21 and are so formed at the opposite end of the frame as to there provide a garment-receiving loop 22 adapted to cooperate with the conventional type of button element herein shown as including a button 23 and a flexible tab 24, one end of which tab is anchored to said frame through the medium of a metal clasp 25 and the other end of which is connected to said button, the usual shank portion of which is adapted to be introduced into and removed from said garment-receiving loop. Referring especially to Figure 3, it will be noted that the anchor clip 25 includes a base flange 26 and a clamp-flange 27 formed integral with each other along a line of fold 28, the base flange being provided at its opposite ends with a pair of holding lugs 29 adapted to be crimped or folded into anchoring engagement with the side arms of the wire frame 20 and the clamp-flange being provided with an inwardly turned gripping margin or edge 30 which is adapted to impinge against one end of the flexible tab 24 and thus anchor it to the wire frame through the medium of said anchor clip as the clamp-flange thereof is moved into its anchoring position shown in Figure 11.

As will be understood from Figures 1 and 5, a suitable type of conventional power operated punch press, modified as required and indicated generally by the numeral 31, is employed as a basic or primary unit of the assembling machine herein illustrated as embodying the present invention. Generally speaking the punch press 31 includes a table-like base 32, on which is supported a frame 33, in the upper end of which is journaled a crank shaft 34, provided intermediate its ends with a crank 34' and carrying at one end a driven gear 35, meshing with a driving gear 36, secured to one end of a power shaft 37, suitably mounted, as shown in Figure 5, and adapted to be driven from any suitable source of power, such as an electric motor 38, through the medium of a pair of pulleys 39 and 40 operatively connected to each other by a belt 41, said pulleys being respectively connected to the shaft of the motor 38 and to the power shaft 37. The press 31 further includes the usual bolster plate 42 and ram 43, the latter of which is connected to the crank 34' of the shaft 34 by the usual pitman 44 and is guided in its vertical reciprocation by the ram guides 45. Between the driven gear 35 and its associated crank shaft 34, there is provided the usual clutch 46, which is adapted to so respond to the operation of a suitable control 75

lever 47 that said gear and said shaft may be conveniently connected to and disconnected from each other at will and maintained in a connected or disconnected relation for so long a period as the operator may desire.

As shown most clearly in Figure 1, the machine includes an endless chain-like conveyor, which is indicated generally by the numeral 48 and comprises a base 49, carried by and suitably connected to the bolster plate 42. At each end of the conveyor base 49 there is suitably connected a pair of bearing blocks 50-53, between which are supported, as on pins or shafts 51, a pair of sprockets 52-53, which are accommodated within suitable notches 54 formed in said base at opposite ends thereof, only one of such notches being shown and that appearing in Figure 2.

Supported by and suitably connected to the conveyor base 49 are a pair of vertically disposed guide rails 55-56, which extend from one end of the machine to the other in a parallel and contiguous relation to the longitudinal center line of said base. To that end of the guide rail 55 nearest the discharge end of the machine there is suitably connected a frame-supporting rail 55', which, as shown in Figure 5, is spaced from said guide rail and as shown in Figure 1, is provided with an arcuate finger 57 following the periphery of the sprocket 53 to the extent of approximately 90° and adapted to aid in supporting the assembled clasps preparatory to their being released from the conveyor 48.

The guide rails 55-56 are adapted to accommodate there-between, and thus guide along a definite path, the upper reach of an endless conveyor chain 58 which, through means herein-after particularly described, is moved step-by-step over the sprockets 52 and 53 in the direction indicated by the arrow A of Figure 1. As will be best understood from Figures 1, 6 to 11, 15 and 17, the chain 58 includes a plurality of carriages 59 pivotally connected to each other in series by suitable links 60. Each of the carriages includes a carriage block 61 which is formed with a slot 62 extending lengthwise thereof, the slots being adapted to receive the ends of the links which are held in their respective chain-forming positions by suitable link-supporting pins or rivets 63.

The carriages 59 are adapted to receive at the feed-end of the conveyor 48 the component elements of the clasps, namely, the anchor clips 25, the wire frames 20 and the button-carrying tabs 24, which elements are moved in one group after another in unison with the conveyor from right to left, reference being had to Figure 1, in order that the assembling operations to be hereinafter more particularly described may be carried out and the completed units discharged at the delivery end of the machine in the condition of that unit appearing at the extreme left in Figure 15.

In order that the anchor clips 25, when delivered to the carriages 59, may be held thereon in definite positions, each carriage block 61 is provided in its upper face, reference being had especially to Figure 11, with a clip-receiving recess 64 adapted to accommodate the base flange 26 of the respective anchor clips.

At opposite ends of the recess 64, the carriage block 61, as clearly shown in Figure 15, is provided with a pair of lugs 65, which define the longitudinal extent of said recess. The lugs 65 are relieved, as are the ends of the carriage blocks 61, so as to provide clearance slots 66, which are adapted to permit the entrance of a suitable

crimping tool 67 (Figs. 1 and 8) by which the lugs 29 of the respective anchor clips 25 are folded into anchoring engagement with the side arms of the respective wire frames, as will hereinafter more clearly appear. As shown most clearly in Figure 15, each carriage block 61 is provided, intermediate the lugs 65 thereof, with a tab-supporting lug 68. From an inspection of Figures 10 and 11, it will be understood that each supporting lug 68 presents an upper inclined face on which the tabs 24 are initially supported, in part. Also from Figures 10 and 11, it will be understood that the relatively wide rear faces of the supporting lugs 68 are disposed in the plane of the rear faces of the respective carriage blocks 61 and that the relatively narrow front faces of said lugs are so disposed with relation to the clip-receiving recesses 64 of said blocks as to guard against undue rearward displacement of the clips 25 after having been delivered to their proper positions on the carriages 59. As shown most clearly in Figures 11 and 15, the supporting lugs 68 are each provided with a recess 69 adapted to accommodate such portions of the tabs 24 as may be temporarily depressed slightly out of its normal plane under the impinging action of a tab-positioning plunger 70, which, as shown in Figure 8, is located at the rear of the crimping tool 67 in a spaced relation thereto, said plunger being hereinafter more particularly described and adapted, as will later appear, to insure proper positioning of the tabs in abutting relation to the respective clips 25 before their clamp-flanges 27 are moved into tab-anchoring positions. Here it may be well to mention that it is necessary to insure proper positioning of the lower ends of the tabs 24 transversely of themselves so that they will be centered between the holding lugs 29 of the anchor clips 25 in order that such lugs may be crimped into anchoring engagement with the side arms of the respective wire frames 20 without impinging on the side margins of said tabs, and to this end there is provided a tab-centering tool 200. The centering tool 200 is suitably connected to the ram 43 for movement therewith and is provided with a pair of tapered fingers 201 which are adapted to straddle the respective tabs 24 as the ram moves downwardly and shift them transversely in either one direction or the other, as the case may require, so that they will assume a centered relation between the holding lugs 29 of their respectively associated anchor clips 25 before being advanced from a position of rest beneath the centering tool to a position of rest beneath the tab-positioning plunger 70.

As will be understood from an inspection of Figure 15, the wire frames 20 are positioned on the respective carriages 59 following the successive introduction of the anchor clips 25, said frames being so shaped that their side arms are adapted to assume such positions when resting on the base flanges 26 of said clips that they (as shown in connection with the second and third carriage from the right in Fig. 15) engage or substantially engage the inner faces of the up-standing or uncrimped anchor lugs 29 and are slightly spaced from the opposite ends of the respective up-standing clamp-flanges 27. In order that the rearwardly diverging portions of the side arms of the wire frames 20 may be accommodated intermediate the lugs 65, such lugs, as best shown in Figures 14 and 15, are so spaced from each other and are so beveled rearwardly that they are adapted to engage or substantially engage the diverging portions of said frames and

thus serve to hold them against any undue shifting transversely of themselves.

Referring to Figures 4, 7 to 11 and 15 to 17, it will be noted that to the rear face of each carriage block 61 there is suitably connected, as by the link-supporting pins 63 (Fig. 17), a plate 71, one end of which is flush with the forward end of its associated carriage block (regard being had to the travel of the conveyor chain 58 in the direction indicated by the arrow A in Figs. 1 and 17) and the other end of which terminates in close proximity to the forward end of the next following carriage block. That portion of each plate 71 which is connected in a face-to-face relation to its associated carriage block 61 is provided with a pair of upwardly and rearwardly extending tab supporting arms 72, which, as will be understood from Figures 1, 6, 14, 15 and 16, are spaced from each other and lie in a common inclined plane.

As best shown in Figures 9, 10 and 11, the tab-supporting arms 72 are so spaced with relation to the rear face of the respective tab-supporting lugs 68 as to there provide a channel, adapted to so receive the retaining sleeve 21, by which the meeting ends of the respective wire frames 20 are held together in an abutting relation, that said sleeve engages the front faces of said tab-supporting arms and the rear face of said tab-supporting lug, with the result that the wire frame is held against displacement longitudinally of itself. Since the wire frames 20 are held, in the manner just described, against displacement longitudinally of themselves and are also held, as previously described, against shifting transversely of themselves by reason of their engagement with the lugs 65, it follows that the anchor clips 25 are positively held against displacement, at the instant the frames are placed in their assembly-positions, due to the fact that the frames and clips become interlocked through the medium of the unclenched holding lugs 29, as shown in connection with the carriage 59 appearing in second position from the right in Figure 15.

Referring again to the tab-supporting arms 72, it will be noted that those of each pair are so formed that they present at their upper ends a pair of forwardly extending ears 73, which are so spaced from each other as to receive therebetween the button-carrying tabs 24, against the side edges of which the ears are adapted to slightly impinge so that the tabs may be temporarily held rearwardly inclined in their supported positions, as shown in Figures 5, 8 and 15, with their lower ends resting on the clips 25 and there positioned to be anchored to them between their flanges 26 and 27.

In order that the gap between the carriages 59 may be closed at such time as they may be traveling in the path of the upper reach of the conveyor chain 58 so as to obviate the possibility of any objects falling into the chain that might obstruct its operation, that portion of each plate 71 which extends from one carriage block 61 to the next following block, as shown in Figure 17, is provided at its upper margin, as will be understood from an inspection of Figures 1, 2, 5, 6 and 15, with a table-like guard flange 74 which is of such length that it extends from one carriage to the next in the upper reach of said chain and is of such width that it transversely bridges the chain-receiving space through which the chain passes intermediate the guide rails 55 and 56.

It is desirable, of course, that the upper reach of the conveyor chain 58 be supported from be-

neath, and to that end there is provided suitable supporting means in the form of rail-like beams 75, 76, 77, which, as will be understood from a consideration of Figures 1, 4, 6, 9, 13, 16 and 17, are disposed between the guide rails 55—56, the beams being spaced lengthwise from each other so as to permit certain essential machine elements, hereinafter particularly described, to be accommodated in the assembly. As the carriage blocks 61 move along the path of travel of the upper reach of the conveyor chain 58, such blocks ride along the beams 75, 76, 77 in engagement with the upper surfaces thereof and are thereby so supported that their upper faces are maintained in a flush relation to the upper edges of the guide rails 55—56.

In order that the conveyor chain 58 may be moved step-by-step along its path of travel, there is provided, as shown in part in Figures 1, 5, 6 and 7, a simple and reliable chain actuating mechanism which includes a reciprocatory slide unit 78. The slide unit 78 comprises a pawl-carrying block 79, suitably mounted on the conveyor base 49 for reciprocation lengthwise thereof. As will be understood from an inspection of Figures 5, 6 and 7, the guide rails 55—56 are cut away so as to accommodate the longitudinal side margins of the block 79, between which and the overlying portions of said rails a sliding fit is afforded. The block 79 is provided intermediate its ends with a recess 80, within which is located a pair of chain-driving pawls 81, pivotally supported on a pin 82 passing through the side walls of said recess and carrying a spacer 83 by which the pawls are held in a spaced relation to each other. Within the recess 80 there is carried a suitable spring 84, which engages the free ends of the pawls 81 and serves to move them upwardly from their chain-driving positions shown in Figure 6. In order to insure a definite driving position of the pawls 81 with relation to the respective carriage 59 as the pawls are moved bodily with their associated block 79 in the direction of the arrow B appearing in Figure 6, each carriage block is notched, as shown at 85 in Figures 6 and 13, so as to accommodate the tapered driving ends of said pawls.

Reciprocation of the pawl-carrying block 79 is effected in a properly timed relation to the machine in its entirety by an oscillatory lever 86, one end of which is connected to a rocker shaft 87, shown in Figure 5 as journaled in a suitable hanger or bearing 88 secured to the lower face of the conveyor base 49. The lever 86 extends upwardly through a suitable slot 89, formed in the conveyor base 49, and terminates at its upper end in a semi-circular head 90, as indicated in Figure 6, which is snugly accommodated for vertical movement within a suitable slot-like opening 90 provided in the pawl-carrying block 79 at the rear end thereof. To the rear end of the shaft 87, there is suitably connected a crank arm 91, the outer end of which carries a trunnion 92, to which is connected, through the medium of a suitable universal joint 93, the lower end of a pitman rod 94. The upper end of the rod 94 is connected, also through the medium of a suitable universal joint 95, to a trunnion 96 carried by a cross-head 97, mounted in a conventional type of guide-frame 98, which is suitably connected to the crank shaft 34 and provided with the usual cross-head adjusting means in the form of a pair of screws 99 by which the cross-head may be adjusted longitudinally of said frame and locked in any desired position so as to obtain any desired extent of eccentricity of

5 said trunnion with respect to said crank shaft. Here it may be well to mention that the extent of eccentricity between the trunnion 96 and the crank shaft 34 determines the extent to which the slide unit 78 is moved back and forth on the conveyor base 49; and since this is true, the setting of said trunnion at the time the machine is assembled should be such that the slide unit 78 reaches the full extent of its forward movement at such time as the carriages 59 assume their proper respective positions with relation to the tab-centering tool 200, hereinbefore described, the crimping tool 67, hereinbefore mentioned, the adjacent flange-clenching tool 100, hereinafter more particularly mentioned, and the tab-folding and button-inserting unit 101 shown most clearly in Figures 5, 9, 10 and hereinafter described in detail.

10 In order that the anchor clips 25 may be delivered to the respective carriages 59 in such manner that they will assume their proper positions on the carriage blocks 61 as previously described and shown at the extreme right in Figure 15, there is provided a conveyor-actuated feed-unit 102, which, as shown in Figure 1, is associated with the upper reach of the conveyor chain 58 relatively near the sprocket 52 over which said chain passes. The feed-unit 102 includes an inclined trough-like chute 103, to which the anchor clips 25 may be delivered by hand or into which they may be released at the upper end thereof from a suitable hopper, not shown. Here it may be well to mention that the bottom wall of the chute 103 is provided with a discard-opening 104 (Fig. 2) of appropriate size and shape to permit any anchor clips that may be wrongly positioned within the chute to drop through the opening as they slide into registration therewith, all properly positioned clips, such as the one shown on the chute in Figure 15, being permitted to pass over said opening and continue in their path of sliding movement. The chute 103 is suitably supported in its inclined position by a bracket 105, mounted on the conveyor base 49, and is equipped with a discharge pipe 106 which is adapted to receive the rejected anchor clips 25, as they pass through the discard-opening 104, and deliver them to a work tray 107, the bottom of which, as shown in Figure 4, underlies the guide-rails 55—56 and is anchored to the conveyor base 49, as by means of screws 108. As shown in Figures 1, 2 and 3, there is arranged within the tray 107 an inverted channel-like support 109 on which the overhanging ends of the wire frames 26 may ride after having been placed on the carriages 59, as by hand, in an over-lying relation to the anchor clips 25 as shown in Figure 15, said support being connected in a face-to-face relation to the guide rail 55 by suitable means such as screws, one of which is shown in Figure 4 and there indicated by the numeral 110. It will be noted when referring to Figure 1 that one end of the support 109 abuts an end wall of the tray 107 and that the web or upper wall 111 of the support, which is flush with the upper face of the guide rail 55, projects beyond the tray and there terminates in a lip 112 by which the wire frames 26 are held clear of said end wall as they pass over the same in their forward course of travel.

15 Referring further to the feed-unit 102, it will be noted, as shown in Figures 1, 2 and 16, that the bracket 105 rotatably supports a vertically disposed escapement wheel 113, the periphery of which is so formed as to there present a series of

lobes 114 and a series of valley-like indentures 115, the lobes and indentures being disposed in an alternate relation to each other. As will be appreciated from an inspection of Figure 16, the lobes 114 and indentures 115 are so dimensioned that as the escapement wheel is rotated step-by-step a definite distance, by means soon to be described, the anchor clips 25 are permitted to move downwardly on the chute 103 and assume, one after another, an interlocking engagement with successive lobes of the escapement wheel, as illustrated in connection with the lower-most anchor clip appearing on the chute in Figure 16. Here it may be well to mention that the anchor clips 25 respectively assume the position of the lower-most clip appearing on the chute 103 in Figure 16 coincident with the completion of each step-by-step movement of the escapement wheel 113 in the direction of the arrow C appearing thereon, each such clip being restrained by that lobe 114 with which it is interlocked until said wheel is again moved in the direction of said arrow, whereupon it is released and permitted to slide down said chute and drop into its proper position on some one of the carriages 59 then at rest in clip-receiving position adjacent the lower end of the chute. It is to be noted that so long as any anchor clip 25 is held in its restrained position by the escapement wheel 113, such other clips as are then carried by the chute 103 and await downward passage thereon are held against such movement, because they, as shown in Figure 16, abut each other and, as a group, engage the clip that is being held in its restrained position by said wheel. However, as the last mentioned anchor clip 25 begins its release-movement in response to displacement of the escapement wheel 113 in the direction of the arrow C, the following clips, as a group, are permitted to move downwardly on the chute 103, with the result that the foremost clip of said group enters into a meshing relation with the lobe 114 next following the one from which said last mentioned clip is then being released and finally, as said escapement wheel comes to rest, assumes the clip-restraining position previously occupied by the clip last to be released.

In order that the escapement wheel 113 may be rotated step-by-step in the direction of the arrow C appearing thereon in Figure 16, there is provided a conveyor-actuated driving mechanism indicated generally by the reference character 116. The driving mechanism 116 is mounted for reciprocation on a supporting-block 117 carried by and suitably connected to the conveyor base 49, said block being disposed in a contiguous relation to the conveyor chain 58 and provided with a pair of upwardly extending guide flanges 118, between which a reciprocatory slide-plate 119 is mounted for movement in a parallel relation to said chain. The plate 119 is formed intermediate its ends with a transverse guide channel 121 adapted for the reception of a slidable chain-engaging dog or finger 122, the chain-engaging end of which is accommodated within a suitable depression 123 provided in the guide rail 55. To the upper face of the slide-plate 119 there is suitably connected a hold-down plate 124, by which the chain-engaging dog 122 is held against upward displacement. As will be understood from an inspection of Figure 17, the dog 122 is held against undue displacement transversely of the slide-plate 119 by reason of the fact that the hold-down plate 124 is provided with a slot-like opening 125, within which is accommodated the

upper end of a stop-pin 126, secured to said dog intermediate its ends. The dog 122 is held in its normal or extended position, as shown in Figure 17, by a suitable spring 127, one end of which is anchored with respect to the hold-down plate 124, as by a screw 128, and the other end of which engages the stop-pin 126. In order that the slide-plate 119 may be properly held down on the supporting-block 117 and yet be permitted to reciprocate thereon, the plate 119 and the hold-down plate 124 are provided with correspondingly located elongated slot-like openings 129-130, respectively, which are adapted to accommodate the shank portion of a shouldered screw 131, the head portion of which overlies said hold-down plate in the marginal vicinity of the slot 130. The hold-down plate 124 is provided at the longitudinal margin thereof nearest the guide-rail 55 with a vertically disposed pawl-carrying flange 132, the upper edge of which, for the most part, is sloped in accordance with the inclination of the chute 103. To the flange 132, relatively near the rear end thereof, there is suitably connected a bearing-pin 133, on which is pivotally supported a driving pawl 134, the upper end of which is adapted, as will herein-after more clearly appear, to so cooperate with a series of pins 135, which are carried by the escapement wheel 113, as to effect step-by-step rotation of that wheel in the direction indicated by the arrow C of Figure 16. The pawl 134, as shown most clearly in Figure 16, carries a downwardly and rearwardly extending trailer arm 136, the lower end of which is adapted to engage and ride along on the upper face of the guide rail 55 as said pawl is moved forwardly in unison with the slide-plate 119. In order that the slide-plate 119, after having completed its forward movement, may be returned to its starting position against a suitable stop 137, shown in Figures 16 and 17, there is provided a tension spring 138, one end of which is suitably anchored to the cover-plate 127 and the other end of which, not shown, may be suitably connected to any appropriate part of the machine.

Taking into account the foregoing description and especially considering Figures 16 and 17, it will be understood that as the conveyor chain 58 is moved step-by-step by the slide unit 78 in the manner previously described, the dog 122, when positioned as shown in Figure 17, will be engaged by successive carriage blocks 61 and moved forwardly in unison with the slide-plate 119. As the dog 122 moves forwardly, in driven engagement with any one of the carriage blocks 61, the pawl 134 engages such one of the pins 135 as may then be located in its path of travel and thereupon causes the escapement wheel 113 to move in the direction indicated in Figure 16 by the arrow C. Shortly before the conveyor chain 58 completes a definite step forward, the chain-engaging end of the dog 122, which presents a cam surface 139 at its leading edge, makes contact with the forward end wall of the depression 123 and is forcibly retracted to such an extent as to be released from engagement with the forward end of its accompanying carriage block 61, whereupon the slide-plate 119 is returned to its normal or starting position under the action of the spring 138, it being noted that during the return movement of the slide-plate said dog passes rearwardly along the side of said associated carriage block and finally assumes its projected position at the rear thereof where it remains in readiness to be engaged by the next following

carriage block. Here it is to be noted that the relationship between the group of pins 135 and the conveyor-actuated driving mechanism 116 is such that rotation of the escapement wheel 113 to the required extent is completed at the instant the dog 122 is cammed out of its driven engagement with the respective carriage blocks 61, the driven engagement of the dog with said blocks being severed at or very slightly prior to such time as the respective blocks come to rest in clip-receiving position at the lower end of the chute 103, as shown in Figure 16. It will be understood, of course, that since the trailer arm 136 of the driving pawl 134 engages the guide rail 55 during the entire course of forward movement of the driving mechanism 116, said pawl is positively restrained against displacement in a clock-wise direction (Fig. 16) about its associated bearing pin 133. Such restraint of the pawl 134 is essential in order that it may exert a positive driving action on the respective pins 135 of the escapement wheel 113 and thus insure proper step-by-step rotation of that wheel. Referring further to Figure 16, it will be appreciated that the pawl 134, incident to each cycle of operation of the driving mechanism 116, engages one of the escapement wheel pins 135 at such time as said pawl reaches its first dotted line position at the right. Thereafter the pawl 134 continues to its second dotted line position at the left which corresponds to the limit of forward movement of the slide-plate 119. When the pawl 134 comes to rest in its second dotted line position, after having carried its engaging pin 135 forwardly to its position of rest, the upper end of said pawl engages the next succeeding pin, as the slide-plate 119 is being returned to its starting position under the action of its associated spring 138, and is thereby moved in a counterclockwise direction (Fig. 16), thus permitting it to pass under that pin, whereupon the trailer arm 136 drops under its own weight into engagement with the guide rail 55, thus conditioning the pawl for another cycle of operation in effecting step-by-step rotation of the escapement wheel 113.

As the anchor clips 25 are placed on the respective carriages 59 by the feed unit 102 in the manner previously described, such carriages continue in their step-by-step movement along the path of travel of the upper reach of the conveyor chain 58 and as they come to rest one after another at some convenient location before reaching the tab-centering tool 200 (which tool, like the crimping tool 67 and the tab-positioning tool 70 and the flange-clenching tool 109, is suitably connected to the ram 43 for vertical reciprocation therewith) the machine operator places the wire frames 20 on the carriage blocks 61, as shown at the right in Figure 15, and then places the button-carrying tabs 24 on the supporting arms 72 where they are held supported in a proper relation to their associated anchor clips. As the carriages 59 successively come to rest beneath the tab-centering tool 200, the ram 43 moves downwardly carrying said tool with it into a straddling relation to the respective tabs 24 with the result that such tabs are shifted transversely of themselves by one or the other of the fingers 201, as the case may require, and are thereby accurately centered between the holding lugs 29 of their associated anchor clips 25. Following each tab-centering operation by the tool 200, the ram 43 is returned to its initial position. As the carriages 59 are successively moved to a position of rest beneath the crimping tool 67, the ram 43

moves downwardly carrying the crimping tool with it, with the result that the holding lugs 29 of the respective anchor clips 25 are folded or crimped inwardly by said tool into anchoring engagement with the side arms of the individual wire frames 20. Following each lug-crimping operation by the tool 67, the ram 43 and its associated crimping tool are returned to their initial position. Here it is to be noted that the tab-positioning plunger 70, which is normally held in its projected position by a suitable compression spring 140, moves in unison with the crimping tool 67 and in doing so engages the button-carrying tabs 24 and urges the lower ends thereof downwardly along the inclined face of the respective supporting lugs 68 so as to insure proper abutting positioning of the tabs with relation to the anchor clips 25 before the flanges 26 and 27 thereof are moved relatively into clamping engagement with said tabs by the flange-clenching tool 109.

Following each lug-crimping operation of the tool 67, the conveyor chain 58 is advanced another step, thus successively moving each carriage 59 from its prior position of rest beneath said tool to a position of rest beneath the flange-clenching tool 109. As each carriage 59 assumes its position of rest beneath the tool 109, the ram 43 is moved downwardly carrying said tool with it, with the result that the clamp-flange 27 of the anchor clip 25 is moved downwardly towards the base flange 28, thus causing the inwardly turned gripping margin or edge 30 of said clamp-flange to impinge against the button-carrying tab 24 and thereby anchor such tab to the wire frame 20.

As the button-carrying tabs 24 are successively anchored to the wire frames 20, thus completing the assembly operations by which the wire frames, the anchor clips 25 and button carrying tabs 24 are united in producing the respective clasps, such clasps are advanced step-by-step in accordance with the movement of the upper reach of the conveyor chain 58 and are successively brought to rest in such relation to the tab-folding and button-inserting unit 101 as to enable that unit to fold said tabs out of their supported positions on the arms 72 (Figs. 5 and 15) into an overlying relation to their associated wire frame 20, as will be understood from an inspection of Figures 9 and 10, and thereupon move the buttons 23 forwardly from their initial positions intermediate the side arms of the respective wire frames into the garment receiving loops 22 where the shank portions of said buttons are frictionally held, thus maintaining the button-carrying tabs in a substantially flat condition as shown in Figures 11, 14 and 15.

Referring more particularly to the tab-folding and button-inserting unit 101, it will be noted that such unit includes a tab-folding arm 141, which, as shown in Figures 5, 9 and 10, is pivotally connected to the upper end of a suitably supported bracket 142. The arm 141 is normally held in its position shown in Figure 5 by a spring 143, one end of which is suitably connected to said arm and the other end of which is anchored to the punch press frame 33. The arm 141 carries a laterally extending pin 144, which is located in the vertical path of movement of a cam-plate 145, suitably connected to the ram 43 for vertical movement therewith. The plate 145 terminates at its lower end in a cam 146 which is of such contour that it is adapted to so displace the cooperatively related pin 144 as to cause the arm 141 to move against the action of the spring 143, from

its normal position (Fig. 5) to a definite extent in the direction of the arrow D (Fig. 9) incident to the completion of each down stroke of the ram 43, said spring then being adapted to return the arm 141 to its normal position as the ram returns to its starting position. As shown most clearly in Figure 13, the arm 141 carries at its outer end a pair of side plates 147, between which is pivotally supported a tab-engaging latch 148, provided with a notch-like detent 149 (Figs. 9 and 10) and carrying a rearwardly extending guide finger 150, the lower face of which is slightly curved throughout its length and merges with the upper wall of said detent. The latch 148 is provided with a forwardly extending trip finger 151, between which and the overhanging end of the arm 141 there is carried a compression spring 152 serving to normally maintain said latch in tab-engaging position with its guide finger 150 abutting against the lower face of said arm, as shown best in Figure 9. Referring to Figures 5 and 9, it will be understood that as the arm 141 is moved in the direction of the arrow D (Fig. 9) the upper or free end of the button-carrying tab 24 will be engaged by a suitably curved guide strip 153, one end of which is let into said arm relatively near the pin 144 where it is anchored by a set screw 154 and the other end of which terminates adjacent the rear end of the guide finger 150. After the tab 24 has been engaged by the guide strip 153 and as the arm 141 continues its movement in the direction of the arrow D, the free end of said tab will slide along said strip and thence on to the guide finger 150 by which it is guided into the detent 149, as shown in Figure 8, where it remains until automatically released. Release of the tab 24 from the detent 149 is automatically effected, due to the fact that at or about the instant the arm 141 reaches the full extent of its downward movement the latch 148 is tilted a sufficient distance, as shown in Figure 10, to permit the button-end of the tab to escape from the detent, such escape being facilitated by reason of the fact that the extreme end of the guide finger 150 then impinges on the button-end of the tab, tending to force the same downwardly. Here it may be well to mention that the tilting action of the latch 148 is effected due to the fact that its trip finger 151 engages a suitable stationary stop 155 as the arm 141 approaches the lower limit of its downward movement and thereby causes the latch to move in a counterclockwise direction against the action of the spring 152, reference being had to Figure 10, while said arm is completing its downward movement, the spring serving to return the latch 148 to its normal position as the arm 141 begins its return movement to normal position under the action of its associated spring 143 hereinbefore mentioned in connection with Figure 5.

At the instant the button-end of the tab 24 is released from the latch 148, the button 23 assumes a position of temporary rest, as shown in Figure 10, with its shank portion disposed intermediate the side arms of the wire frame 20 and in readiness to be moved forwardly into the garment-receiving loop 22, within which it assumes its final position as shown in Figure 11. Displacement of the button 23 from its position (Fig. 10) to its position (Fig. 11) is effected by a button-engaging finger 156 mounted on and carried by a reciprocatory slide block 157, which is normally held in its retracted position, as shown in Figure 10, by a tension spring 158, one end of which is suitably connected to the rear of said block and

the other end of which is anchored to the punch press frame 33, as shown in Figure 5. The slide-block 157 is mounted on the conveyor base 49 for reciprocatory movement beneath the upper reach 5 of the conveyor chain 58 and is accommodated between adjacent ends of the beams 75-76, as will be understood from an inspection of Figures 1, 11, 13, said beams being located intermediate the guide rails 55-56, as previously explained, and said rails being cut away as shown at 159 (Figs. 11 and 13) in order that said block may be further accommodated for reciprocation. The front end of the slide-block 157 overhangs the conveyor base 49, as shown most clearly in Figures 5, 10, 11, 14, and is there straddled by a guide-block 160, which is suitably connected to said base, as by screws 161 appearing in Figure 1. The stationary stop 156 hereinbefore mentioned is suitably connected to the upper face of the guide-block 160, as shown most clearly in Figures 9 and 10, said stop being located adjacent a rearwardly projecting ledge 162 (Figs. 9, 10, 11) with which said guide-block is provided and on which the ends of the respective garment retaining loops 22 20 of the wire frames 20 are supported as the tab-folding and button-inserting operations are carried out. Here it may be well to mention that the loop ends of the wire frames 20 pass onto the ledge 162 from between a pair of guide arms 163-164 which are suitably connected to the guide-block 160, as shown in Figure 1, and project therefrom in a contiguous relation to the upper reach of the conveyor chain 58. These guide-arms 163-164 are adapted to receive there-between the loop ends of the wire frames 20 as such frames approach the crimping tool 67 and function to retain them against undue vertical displacement during such time as the clips 25 are being anchored to said frames by the crimping tool and during such time as the button-carrying tabs 24 are being anchored to said clips by the flange-clenching tool 190.

Referring further to the tab-folding and button-inserting unit 101, it will be noted that the slide-block 157, as best shown in Figure 11, is provided with a vertical opening 165, adapted to receive the lower end of a bell-crank lever 166, by which said block is moved forwardly against the action of its associated return spring 158, as and for the purpose hereinafter more particularly described. Referring especially to Figures 1, 10, 11, it will be noted that the guide-block 160 is provided at one end thereof with a vertical post-like flange 167 to which is connected an upwardly extending inclined channel-like guide 168, the bottom wall 169 of which is adapted to receive a pair of bolts 170 by which the guide, as a unit, is connected to said flange, and the side walls 171 of which guide are adapted to accommodate a bearing pin 172 on which the bell-crank lever 166 is pivotally supported. Within the guide 168 there is located a reciprocatory push-bar 173 which is provided intermediate its ends with a pair of elongated openings 174, adapted to accommodate a pair of retaining pins 175 on which said bar is adapted to slide, the retaining pins being carried by and suitably anchored to the side walls 171 of said guide. To the lower end of the push-bar 173, there is bolted, or otherwise suitably connected, a thrust-block 176, the lower end of which slidably engages the upper end of the bell-crank lever 166, as will be understood from an inspection of Figures 9 and 11. The upper end of the push-bar 173 is equipped with a cam roller 177, which is adapted to be engaged, once for each

revolution of the crank shaft 34, by a relatively short cam 178 projecting from the peripheral face of a cam plate 179 associated with said shaft for rotation in unison therewith. In order to lend rigidity to the channel-like guide 168, such guide is provided at its upper end with a yoke-like stabilizer 180, the leg portion 181 of which is suitably connected to said guide, as by screws 182, and the diverging arm portions 183 of which straddle the hub portion 184 of the cam plate 179. The cam 178 is so positioned with relation to the crank 34' of the shaft 34 that at or about the instant the button-carrying tab 24 assumes its folded position shown in Figure 10, said cam engages the roller 177 and so acts on it as to move the push-bar 173 downwardly, thus causing the thrust-block 166 to so act on the upper end of the bell-crank lever 166 as to move that lever from its position shown in Figure 5 to its position shown in Figure 11. During such movement of the bell-crank lever 166, the lower end of the same so acts on the slide-block 157 as to move it, against the action of the spring 158, from its position shown in Figure 5 to its position shown in Figure 11. As the slide-block 157 is moved in the manner just described, the button-engaging finger 156 is moved from its normal position shown in Figure 10 into engagement with the button 23 and carries it forwardly into the garment-receiving loop 22 of the wire frame 20 where it assumes its final position of rest, as shown in Figure 11, at the closed end of said loop as the slide-block completes its forward movement under the action of the bell-crank lever 166. Incident to completion of the button-inserting operation, as just described, the cam 178 releases its downward operating influence on the push-bar 173, thus permitting the spring 155 to return the slide-block 157 to its normal position, shown in Figure 10, and at the same time allowing that spring to so act on the push bar, by way of the bell-crank lever 166 and the slide-block 157, as to return said bar to its elevated or normal position shown in Figure 5.

Here it may be well to point out in connection with the tab-folding operation that an essential requirement resides in the fact that the button-carrying tab 24 and the wire frame 20 be properly registered, as illustrated in Figure 13, at such time as the tab is released from the detent 149 of the tab-engaging latch 148, so that the button 23 will unobstructedly enter between the side arms of said frame and there assume its position at the entrance end of the garment-receiving loop 22, as shown in Figure 10. In order to meet the foregoing requirement, the tab-folding arm 141 is provided at its outer end with a pair of indexing plates 185, which, as shown in Figure 13, are connected, respectively, to the side plates 147 by a pair of bolts 186 (Fig. 10) which also serve to connect said side plates to the tab-folding arm. The indexing plates 185, as will be understood from an inspection of Figures 5 and 9, are provided with a pair of ears 187 which are spaced from each other a distance slightly greater than the width of the button-carrying tabs 24 in order that such tabs and their respectively associated wire frames 20 may be accommodated therebetween and thus brought into proper registration at or about the instant the tab-folding arm 141 reaches the limit of its downward movement, as shown in Figure 13 where said ears appear in vertical section.

It is desirable that the outer end of the garment-receiving loop 22 of the respective wire

frames 20 be held with reasonable firmness on the ledge 162 (Figs. 5, 9, 10, 11, 12, 14) during such time as the tab-folding and button-inserting operations are being carried out by the unit 161, and to that end there is provided a hold-down finger 188, beneath which said frames pass as they emerge from between the guide arms 163 and 164. The hold-down finger 188 is supported at one end by an arm 189, suitably connected, as shown most clearly in Figures 12 and 14, to the post-like flange 167 of the guide-block 160, the other end of the hold-down finger being free, as shown in Figure 14, so as to permit the wire frames 20 and their respectively associated overlying button-carrying tabs 24 to move, as completed units, free and clear of said finger in their passage toward the discharge end of the conveyor 48 where they are released from the conveyor chain 58 as they pass over the arcuate finger 57. From an inspection of Figure 12 it will be understood that the upper face of the guide arm 164 lies in the plane of the upper face of the ledge 162 so as to facilitate passage of the wire frames 20 onto such ledge as they pass from between the guide arms 163—164, and that the hold-down finger 188 is so bent downwardly in the vicinity of its point of connection with the arm 189 that the wire frames successively move under said hold-down finger before they pass from beneath the guide arm 163 when proceeding to a position of rest, with relation to the unit 161, where the tab-folding and button-inserting operations are carried out.

In view of the foregoing description of the machine herein illustrated as an embodiment of the present invention, it is believed that no further discussion of the same from either a structural or a functional standpoint is necessary to a complete understanding of it by those skilled in the art to which it pertains.

Although only one form of the invention is herein shown and described, it will be understood that various modifications may be made with respect to the present embodiment without departing from the spirit of the invention or the scope of the following claims.

What is claimed is:

1. In a machine for use in assembling clasps of the type including a frame, an anchor clip and a button element, said frame being provided at one end with a garment receiving loop and said button element including a flexible tab connected at one end to said frame through the medium of said clip and provided at its other end with a button having a shank portion adapted to enter said loop and be held therein by the side arms of said frame; a conveyor adapted to receive said frames, clips and button elements and move them as one group after another to a definite assembling position, and a tab-folding and button inserting unit operating on said button elements as said groups assume said assembling position to so fold said tabs as to position their associated buttons at the entrance ends of said garment-receiving loops and thereupon move the same into such loops, said unit comprising a movable tab-folding arm adapted to slidably engage the free ends of said tabs and move them forwardly and downwardly into a contiguous relation to said frames, a tab-engaging latch carried by said arm and located in the path of sliding movement of said tabs to arrest such movement as such tabs approach a contiguous relation to said frames, means for tripping said latch out of restraining engagement with said tabs as they

assume a contiguous relation to said frames and for moving said latch into depressing engagement with said tabs so as to insure their being held in a contiguous relation to said frames, and means operating on said buttons while their associated tabs are maintained in a contiguous relation to said frames to move said buttons into said loops.

2. In a machine for use in assembling clasps of the type including a frame, an anchor clip and a button element, said frame being provided at one end with a garment receiving loop and said button element including a flexible tab connected at one end to said frame through the medium of said clip and provided at its other end with a button having a shank portion adapted to enter said loop and be held therein by the side arms of said frame; a conveyor adapted to receive said frames, clips and button elements and move them as one group after another to a definite assembling position, and a tab-folding and button inserting unit operating on said button elements as said groups assume said assembling position to so fold said tabs as to position their associated buttons at the entrance ends of said garment-receiving loops and thereupon move the same into such loops, said unit comprising a movable tab-folding arm adapted to slidably engage the free ends of said tabs and move them forwardly and downwardly into a contiguous relation to said frames, a tab-engaging latch carried by said arm and located in the path of sliding movement of said tabs to arrest such movement as such tabs approach a contiguous relation to said frames, means for tripping said latch out of restraining engagement with said tabs as they assume a contiguous relation to said frames and for moving said latch into depressing engagement with said tabs so as to insure their being held in a contiguous relation to said frames, indexing means carried by said arm and cooperating with said tabs and their associated frames to insure registration between such tabs and such frames at the instant said latch is tripped out of restraining engagement with the respective tabs, and means operating on said buttons while their associated tabs are maintained in a contiguous relation to said frames to move said buttons into said loops.

3. In a machine for use in assembling a clasp of the type including a frame and a button element, said frame being provided at one end with a garment receiving loop and said button element including a flexible tab connected at one end to said frame and provided at its other end with a button having a shank portion adapted to enter said loop; a prime mover; a conveyor operatively connected to said prime mover and adapted to receive said frame and button element and move them as a group along a definite path of assembly, tab folding means operatively connected to said prime mover and timed with relation to said conveyor and located in a definite position along said path and there operating to engage said tab and so fold it as to position its associated button at the entrance end of said garment receiving loop, and button inserting means operatively connected to said prime mover and timed with relation to said conveyor and also located in a definite position along said path and there operating to engage said button after its associated tab has been folded and move said button into said loop.

4. In a machine for use in assembling a clasp of the type including a frame, an anchor clip and a button element, said frame being pro-

vided at one end with a garment receiving loop and said button element including a flexible tab connected at one end to said frame through the medium of said clip and provided at its other end with a button having a shank portion adapted to enter said loop and be held therein by the side arms of said frame; a prime mover; a conveyor operatively connected to said prime mover and adapted to receive said frame, clip and button element and move them as a group to successive assembling positions; crimping means operatively connected to said prime mover and timed with relation to said conveyor and operating on said clip as said group assumes one of said assembling positions to connect said clip to said frame; clenching means operatively connected to said prime mover and timed with relation to said conveyor and operating on said clip as said group assumes another of said assembling positions to connect said clip to one end of said flexible tab; and tab-folding and button inserting means operatively connected to said prime mover and timed with relation to said conveyor and operating on said tab as said group assumes still another of said assembling positions to so fold said tab as to position its associated button at the entrance end of said garment receiving loop and thereupon move said button into said loop.

5. In a machine for use in assembling a clasp of the type including a frame, an anchor clip and a button element, said frame being provided at one end with a garment receiving loop and said button element including a flexible tab connected at one end to said frame through the medium of said clip and provided at its other end with a button having a shank portion adapted to enter said loop and be held therein by the side arms of said frame; a conveyor including a carriage adapted to receive said frame, clip and button element, said carriage including retaining means for holding said frame, clip and button element in a definite grouped relation to each other; a prime mover; conveyor actuating means operatively connected to said prime mover for effecting step-by-step movement of said carriage, whereby said frame, clip and button element are moved as a group to successive assembling positions; crimping means operatively connected to said prime mover and timed with relation to said conveyor and operating on said clip as said group assumes one of said assembling positions to connect said clip to said frame; clenching means operatively connected to said prime mover and timed with relation to said conveyor and operating on said clip as said group assumes another of said assembling positions to connect said clip to one end of said flexible tab; and tab-folding and button inserting means operatively connected to said prime mover and timed with relation to said conveyor and operating on said tab as said group assumes still another of said assembling positions to so fold said tab as to position its associated button at the entrance end of said garment receiving loop and thereupon move the same into said loop.

6. In a machine for use in assembling a clasp of the type including a frame, an anchor clip and a button element, said frame being provided at one end with a garment receiving loop and said button element including a flexible tab connected at one end to said frame through the medium of said clip and provided at its other end with a button having a shank por-

tion adapted to enter said loop and be held therein by the side arms of said frame; a prime mover; a conveyor operatively connected to said prime mover and adapted to receive said frame, clip and button element and move them as a group to successive assembling positions; tab-positioning means operatively connected to said prime mover and timed with relation to said conveyor and operating on said tab as said group assumes one of said assembling positions to urge one end of said tab into a definite position with relation to said clip; and clenching means operatively connected to said prime mover and timed with relation to said conveyor and operating on said clip to connect said clip to its associated tab after said one end of that tab has been urged into said definite position.

7. In a machine for use in assembling a clasp of the type including a frame, an anchor clip and a button element, said frame being provided at one end with a garment receiving loop and said button element including a flexible tab connected at one end to said frame through the medium of said clip and provided at its other end with a button having a shank portion adapted to enter said loop and be held therein by the side arms of said frame; a prime mover; a conveyor operatively connected to said prime mover and adapted to receive said frame, clip and button element and move them as a group to a definite assembling position; and tab-folding and button inserting means operatively connected to said prime mover and timed with relation to said conveyor and operating on said button elements as said group assumes said assembling position to so fold said tab as to position its associated button at the entrance end of said garment receiving loop and thereupon move said button into said loop, said tab-folding and button inserting means including a movable tab-folding arm adapted to engage said tab and fold it into contiguous relation to its associated frame so as to position said button at the entrance end of said loop; and a movable button-engaging element operatively connected to said prime mover and timed with relation to said conveyor and operating on said button while its associated tab is maintained in a contiguous relation to said frame to move said button into said loop.

8. In a machine for use in assembling a clasp of the type including a frame, an anchor clip and a button element, said frame being provided at one end with a garment receiving loop and said button element including a flexible tab connected at one end to said frame through the medium of said clip and provided at its other end with a button having a shank portion adapted to enter said loop and be held therein by the side arms of said frame; a prime mover; a conveyor operatively connected to said prime mover and adapted to receive said frame, clip and button element and move them as a group to a definite assembling position; and tab-folding and button inserting means operatively connected to said prime mover and timed with relation to said conveyor and operating on said button elements as said group assumes said assembling position to so fold said tab as to position its associated button at the entrance end of said garment-receiving loop and thereupon move said button into said loop, said tab-folding and button inserting means including a movable tab-folding arm adapted to slidably engage the free end of said tab and move it for-

wardly and downwardly into a contiguous relation to said frame, a tab-engaging latch carried by said arm and located in the path of sliding movement of said tab to arrest such movement as such tab approaches a contiguous relation to said frame, and a movable element operating in a timed relation to said arm to engage said button while its associated tab is maintained in a contiguous relation to said frame and at that time move said button into said loop.

9. In a machine for use in assembling a clasp of a type including a frame and a button element, said frame being provided at one end with a garment receiving loop and said button element including a flexible tab connected at one end to said frame and provided at its other end with a button having a shank portion adapted to enter said loop; a prime mover; a conveyor operatively connected to said prime mover and adapted to receive a frame and a button element and move them as a group to a definite assembling position; and a tab-folding and button inserting unit operatively connected to said prime mover and timed with relation to said conveyor and operating on said button element as said group assumes said assembling position to so fold said tab as to position its associated button at the entrance of said garment receiving loop and thereupon move said button into said loop, said unit comprising a movable tab-folding arm operating in definite time-relation to said conveyor and adapted to engage said tab and fold it into contiguous relation to its associated frame so as to position said button at the entrance end of said loop, and a button engaging finger operatively connected to said prime mover and timed with relation to said conveyor and operating in a definite time-relation to said tab-folding arm and adapted to engage said button while its associated tab is maintained in a contiguous relation to said frame and move said button into said loop.

10. In a machine for use in assembling a clasp of a type including a frame and a button element, said frame being provided at one end with a garment receiving loop and said button element including a flexible tab connected at one end to said frame and provided at its other end with a button having a shank portion adapted to enter said loop; a prime mover; a conveyor operatively connected to said prime mover and adapted to receive a frame and a button element and move them as a group to a definite assembling position; and a tab-folding and button inserting unit operatively connected to said prime mover and timed with relation to said conveyor and operating on said button element as said group assumes said assembling position to so fold said tab as to position its associated button at the entrance end of said garment receiving loop and thereupon move said button into said loop, said unit comprising a movable tab-folding arm operating in a definite time-relation to said conveyor and adapted to slidably engage the free end of said tab and move it forwardly and downwardly into a contiguous relation to said frame, a tab-engaging latch carried by said arm and located in the path of sliding movement of said tab to arrest such movement as said tab approaches a contiguous relation to said frame, and a button engaging finger operatively connected to said prime mover and timed with relation to said conveyor and

21

operating in a definite time-relation to said tab-folding arm and adapted to engage said button while its associated tab is maintained in a contiguous relation to said frame and move said button into said loop.

11. In a machine for use in assembling a clasp of a type including a frame and a button element, said frame being provided at one end with a garment receiving loop and said button element including a flexible tab connected at one end to said frame and provided at its other end with a button having a shank portion adapted to enter said loop; a prime mover; a conveyor operatively connected to said prime mover and adapted to receive a frame and a button element and move them as a group to a definite assembling position; and a tab-folding and button inserting unit operatively connected to said prime mover and timed with relation to said conveyor and operating on said button element as said group assumes said assembling position to so fold said tab as to position its associated button at the entrance end of said garment receiving loop and thereupon move the same into said loop, said unit comprising a movable tab-folding arm operating in a definite time-relation to said conveyor and adapted to slidably engage the free end of the said tab and move it forwardly and downwardly into a contiguous relation to said frame, a tab-engaging latch carried by said arm and located in the path of sliding movement of said tab to arrest such movement as said tab approaches a contiguous relation to said frame, means for tripping said latch out of restraining engagement with said tab as it assumes a contiguous relation to said frame and for moving said latch into depressing engagement with said tab so as to insure its being held in a contiguous relation to said frame, and a button engaging finger operatively connected to said prime mover and timed with relation to said conveyor and operating in a definite time-relation to said tab-folding arm and adapted to engage said button while its associated tab is maintained in a contiguous relation to said frame and move said button into said loop.

12. In a machine for use in assembling a clasp of a type including a frame and a button element, said frame being provided at one end with

22

a garment receiving loop and said button element including a flexible tab connected at one end to said frame and provided at its other end with a button having a shank portion adapted to enter said loop; a prime mover; a conveyor operatively connected to said prime mover and adapted to receive a frame and a button element and move them as a group to a definite assembling position; and a tab-folding and button inserting unit operatively connected to said prime mover and timed with relation to said conveyor and operating on said button element as said group assumes said assembling position to so fold said tab as to position its associated button at the entrance end of said garment receiving loop and thereupon move the same into such loop, said unit comprising a movable tab-folding arm operating in a definite time-relation to said conveyor and adapted to slidably engage the free end of said tab and move it forwardly and downwardly into a contiguous relation to said frame, a tab-engaging latch carried by said arm and located in the path of sliding movement of said tab to arrest such movement as said tab approaches a contiguous relation to said frame, means for tripping said latch out of restraining engagement with said tab as it assumes a contiguous relation to said frame and for moving said latch into depressing engagement with said tab so as to insure its being held in a contiguous relation to said frame, indexing means carried by said tab-folding arm and cooperating with said tab and its associated frame to insure registration between such tab and such frame at the instant said latch is tripped out of restraining engagement with said tab, and a button engaging finger operatively connected to said prime mover and timed with relation to said conveyor and operating in a definite time-relation to said tab-folding arm and adapted to engage said button while its associated tab is maintained in a contiguous relation to said frame and move said button into said loop.
